CLAIM

The ornamental design for a decking element as shown and described.

DESCRIPTION

FIG. 1 is a front elevational view of a decking element showing our new design, the rear elevation view being a mirror image thereto;

FIG. 2 is a left side elevational view thereof, the right side elevation view being a mirror image thereto;

FIG. 3 is a top plan view thereof; and,

FIG. 4 is a bottom plan view thereof.

The decking element is shown with a symbolic break in its length and width. The appearance of any portion of the decking element between the break lines forms no part of the claimed design.

The broken lines in the drawings illustrate portions of the decking element and form no part of the claimed design.

1 Claim, 4 Drawing Sheets
